UNITED STATES PATENT OFFICE.

DANIEL A. WEDMORE, OF PHILADELPHIA, PENNSYLVANIA, ASSIGNOR TO PHILADELPHIA STEEL & WIRE CO., OF PHILADELPHIA, PENNSYLVANIA, A CORPORATION OF NEW JERSEY.

WIRE TIE FOR METALLIC REINFORCES.

No. 919,099.

Specification of Letters Patent. Patented April 20, 1909.

Application filed February 21, 1908. Serial No. 417,107.

To all whom it may concern:

Be it known that I, DANIEL A. WEDMORE, a citizen of the United States, residing in Philadelphia, Pennsylvania, have invented 5 certain Improvements in Wire Ties for Metallic Reinforces, of which the following is a specification.

The object of my invention is to provide an efficient form of wire tie for use in connection with reinforcing bars or rods for concrete construction.

My invention comprises a form of tie capable of modification and particularly adapted for use in tying together the members forming reinforces for girders, beams, posts, columns and the like.

My invention is fully shown in the accompanying drawings, in which:

Figure 1, is a perspective view of one form of tie embodying my invention; Fig. 2, is a perspective view showing the same in position of use; Fig. 3, is a perspective view of another form of tie embodying my invention; Fig. 4, is a perspective view showing the same in the position of use; Fig. 5, is a perspective view of a modified form of the tie shown in Fig. 3; Fig. 6, is a view of still another form of tie somewhat similar to the structure shown in Fig. 1, but arranged to operate in a slightly different manner, and Fig. 7, is a perspective view of the same in the position of use.

In a companion application filed of even date herewith, I have shown a metallic reinforce for concrete construction, the individual metal portions of which are secured together by means of ties of the several forms disclosed herewith.

The most desirable feature in ties of this 40 character is the ability to secure them to the work on the job in a simple and efficient manner; the tie being so constructed and arranged when in place as to prevent dislodgment, and at the same time to permit 45 movement of the members secured together with respect to each other without danger of separation due to such movement.

Referring to the drawings, Fig. 2, shows a tie connection designed for use between 50 longitudinal reinforcing bars 1 and the upper portions 2 of the stirrup; such member being shown in the normal shape before use in Fig. 1. It consists of a wire member having two substantially parallel runs 5 and 5^a, the run 5 being longer than 5^a. The

runs 5 and 5^a are joined by a loop 6, and said runs have hook portions 7 and 7^a, respectively. The loop of this tie is caught under the bar or rod; the runs 5 and 5^a are then brought down over the stirrup projection 2 by lying at right angles to said bar, and then the hooks 7 and 7^a in the order named are caught underneath the bar in the manner clearly shown in Fig. 2. This arrangement permits either member to move 60 with respect to the other, and when the members are assembled in proper relation to each other, such for instance as shown in Fig. 2, the structure may be readily collapsed. It will be noted, however, that in 70 order to permit this collapsing, the longitudinal rods are disposed below the projections 2 of the stirrups; the tie members forming with the bar or rod a bearing in which the projection of the stirrup may 75 turn.

For use in connecting the lower cross-runs of a stirrup with the longitudinal bars, I may use a tie member of the type shown in Figs. 3 and 4, or that shown in Fig. 5. 80 That shown in Figs. 3 and 4, comprises a structure having a loop 8 to engage the rod, from which a run 9 extends terminating in a hook 10 to engage the cross run of the stirrup. Another run 9^a extends from said 85 loop portion 8 and passes over said rod and downwardly in a long curve or loop forming a support or foot; the end of said run being provided with a hook 10^a which is caught over the rod. The foot or support which 90 this form of tie provides, will serve to raise the stirrup above the centering, and at the same time obviates the necessity of using stirrups with their upper ends in engagement with the centering in order to raise 95 them to the proper height to insure the required layer of concrete beneath the beam or girder. This permits the use of straight arm projections for the stirrups.

In Fig. 5, I have shown a form of tie with 100 two supports or feet. This may be used when the metal of the reinforce is particularly heavy.

In Fig. 6, I have shown another form of tie in its normal shape and in Fig. 7, in the 105 position of use. This tie comprises a piece of wire doubled upon itself, and like the first mentioned tie shown in Figs. 1 and 2, it has runs 12 and 12^a of unequal length joined by a loop 13. The long run 12 is 110

provided with a hook 14 lying in the plane of the loop 13 connecting the runs, while the short run 12^a is provided with a hook 14^a lying in a plane at right angles to the hook 14. In the manner of attaching it to reinforcing rods which cross each other as shown in the drawings, the hook 14^a may engage the horizontal rods, while the hook 14 may engage the vertical rods. Such arrangement, of course, depends upon which of the rods the loop 13 of the member is applied, for while it will act equally well when disposed in a position substantially at right angles to the structure shown in Fig. 7, it will be on the opposite side of the crossing portions of the rods.

It is obvious, of course, that other forms of ties capable of performing the function desired in structures of this character may be employed with equal facility, and my invention is not limited to the use of any specific form of tie or those shown herein.

I claim:

1. A wire tie for securing metallic members in contact with each other at their crossing points and permitting hinged movement of either member with respect to the other, said tie having a loop to be engaged by one of said members, runs paralleling said loop-engaged member and arranged to engage and pass over the other member, and hooks carried by said runs for locking the tie to said metallic members.

2. A wire tie for securing a plurality of crossing rods at an angle in contact with each other, said tie having a loop to be engaged by one of said rods, runs paralleling said loop-engaged rod and arranged to engage and pass over the other rod, and hooks carried by said runs for engagement with the rods.

3. A wire tie for securing metallic members in contact with each other at their

crossing points, said tie having a loop to be engaged by one of said members, runs paralleling each other, and hooks disposed toward each other and carried by said runs for locking said tie to the metallic members. 45

4. A wire tie for securing crossing rods in contact with each other at their point of intersection, said tie having a loop to be engaged by one of said rods, runs paralleling one of said rods, and hooks carried by said runs to engage said last mentioned rod whereby the rods are held together so that 50 either one may turn within the tie with respect to the other. 55

5. A wire tie for securing crossing rods in contact with each other at their point of intersection, said tie having a loop to be 60 engaged by one of said rods, runs integral with said loop and terminating in hooks for engagement with said rods whereby they are held together so that either one may turn within the tie with respect to the other, 65 and a support formed by one of said runs between the hooked portions of the same.

6. The combination of a pair of metallic members crossing each other at an angle, and a wire tie for securing said members in contact with each other at their crossing point and permitting hinged movement of either with respect to the other, said tie having a loop to be engaged by one of said members, runs paralleling said loop-engaged 75 member and arranged to engage and pass over the other member, and hooks carried by said runs for locking the tie to said metallic members.

In testimony whereof, I have signed my 80 name to this specification, in the presence of two subscribing witnesses.

DANIEL A. WEDMORE.
